W. K. Houser.

WIRE STRETCHER.

APPLICATION FILED SEPT. 22, 1916.

1,243,940.

Patented Oct. 23, 1917.

UNITED STATES PATENT OFFICE.

WALTER K. HOUSER, OF SPOTTSWOOD, VIRGINIA.

WIRE-STRETCHER.

1,243,940.

Specification of Letters Patent. Patented Oct. 23, 1917.

Application filed September 22, 1916. Serial No. 121,626.

To all whom it may concern:

Be it known that I, WALTER K. HOUSER, a citizen of the United States, residing at Spottswood, in the county of Augusta and 5 State of Virginia, have invented certain new and useful Improvements in Wire-Stretchers, of which the following is a specification.

This invention relates to an improved 10 wire stretcher and has as its primary object to provide a device of this character which may be easily and quickly erected adjacent a post of a fence as for instance a terminal post and operable to simultaneously stretch all of the fence wires of a reach 15 of fence.

The invention has as a further object to provide a device of this character having an improved and simplified stretching 20 mechanism as well as to also provide a simple but effective means for mounting the said mechanism.

And the invention has as a still further 25 object to provide an arrangement whereby the device may be effectually braced to support the stretcher in active position.

Other and incidental objects will appear 30 as the description proceeds and in the drawings wherein I have illustrated the preferred embodiment of the invention and wherein similar reference characters designate corresponding parts throughout the several views:

Figure 1 is a perspective view showing 35 my improved device arranged at the terminal of a fence and particularly showing the clamp employed for engagement with the fence wires,

Fig. 2 is a fragmentary side elevation 40 particularly showing the mounting of the winding shaft employed,

Fig. 3 is a fragmentary perspective view 45 particularly illustrating the double ended worm shaft arranged to coöperate with the winding shaft,

Fig. 4 is a detail perspective view showing 50 the eccentric or crank arranged at the lower extremity of the winding shaft for receiving the chain or flexible element which is operatively engaged with the wire clamp,

Fig. 5 is a fragmentary perspective view 55 showing the forked bracket mounted upon the supporting post of the device with the forks of the said brackets adapted to receive lateral brace members for the said posts.

In carrying out the invention, a post or vertical support 10 is employed which may be formed of metal or other suitable material and adapted to be driven into the ground adjacent the terminal of a fence or any other point therein, as particularly shown in Fig. 1, the terminal of the fence having been conventionally shown for the purposes of illustration. As is usual, 60 spaced posts 11 and 12 respectively are arranged at the said fence terminal and are supported with respect to each other by a brace rod 13 with the vertically spaced fence wires 14 secured to the said posts. Mounted upon the post 10, is a bracket 15 preferably formed from a metal strip connected at its extremities to the said post with the intermediate portion of said strip bent intermediate its ends to provide upper and lower arms 16 and 17 respectively extending laterally from the post with the length of the strip between the said arms seating against the post to be secured thereto by rivets or other suitable fastening devices. 70 Rotatably mounted upon the arms 16 and 17 of the supporting bracket is a vertical winding shaft 18 which extends freely through the uppermost arm 16 and is preferably provided with a swivel connection with 75 the arm 17. Mounted upon the arm 16 is a worm shaft bracket 19 which may be connected to the said arm in any suitable manner as by rivets and freely receives the upper end of the winding shaft 18. At its 80 inner extremity, the bracket 19 is provided with upstanding ears 20 upon which is mounted a double ended worm shaft 21 carrying, as particularly shown in Fig. 3, 85 a worm 22. The terminals of the shaft 21 are, as also particularly shown in Fig. 3, each squared to removably receive a crank 23. Mounted upon the inner extremity of the bracket 19 is a filler plate 24 suitably connected with the said bracket and which receives the upper extremity of the shaft 18 to provide an increased bearing therefor.

Resting upon the said plate, as particularly shown in Fig. 2, is a preferably fibrous packing washer 25 which bears between the plate 24 and a worm wheel 26 fixed upon the upper end of the winding shaft 18 and arranged to coöperate with the worm 22. Thus, actuation of the shaft 21 by the crank 23 will act to rotate the shaft 18 105 while the washer 25 will prevent the worm wheel 26 from grinding against the plate 110

24 when the said shaft is so rotated. In this connection, it is also to be observed that the upper terminal of the bracket 15 slopes downwardly over the bracket 19, the worm 5 22 mounted thereon, and the worm wheel 26, to provide a housing therefor.

Keyed upon the lower extremity of the shaft 18 is an eccentric or crank arm 27 which, as particularly shown in Fig. 4 of the drawings, is provided adjacent the outer extremity thereof with an opening which freely receives a staple 28 and connected to this staple is one end of a chain or other suitable flexible element 29. The free end 10 of the chain 29 is arranged for adjustable engagement with a hook 30 which carries a second hook 31. This hook 31 is, as particularly shown in Fig. 2 of the drawings, adapted for detachable engagement with 20 a wire clamp. This clamp includes vertical coacting clamping strips 32 between which is received the adjacent ends of the wires 14 with the clamps held to engage the said wires by a plurality of vertically spaced 25 bolts or other suitable fastening devices 33. The bolts 33 are preferably provided with wing nuts so that the said clamp may be easily engaged with the fence wires. As will now be observed upon reference to Fig. 1, 30 the bill of the hook 31 is arranged to detachably embrace the clamping strips 32 at a point substantially midway the ends of the clamp.

Formed on the post 10 above and below 35 the bracket 15 are pairs of spaced ears 34 and pivoted between these said pairs of ears are brace bars 35 which, at their free extremities, are suitably engaged with the terminal post 12 of the fence adjacent the 40 upper and lower extremities thereof for supporting the post 10 with respect to the post 12. Connected to the outer side of the post 10, at a point substantially midway the ends thereof is a forked bracket 36, the forks of 45 which are arranged to extend downwardly and laterally to provide outwardly projecting arms 37. Arranged to coact with these arms, are brace members 38, the upper extremities of which are formed with sockets 50 to receive the said arms with the said members extending laterally and outwardly from the post 10 to engage the ground for supporting the post against lateral movement.

As will now be clear, the post may be 55 readily sunk in the ground adjacent the post 12 and the braces 38 arranged in position. The clamping strips 22 are then engaged with the fence wires 14 and the hook 31 engaged about the said strips. The crank 23 60 may then be operated to rotate the shaft 18 when the chain 29 will be wound about the

said shaft to stretch the said fence wires. All of the wires of the adjacent reach of the fence may thus be stretched simultaneously.

It will therefore be seen that I provide 65 a very efficient construction for the purpose set forth and a stretcher which may be easily arranged in active position. It will also be seen that I provide an exceedingly simple and effective mounting for the stretching 70 mechanism upon the supporting post of the device while, at the same time, said mechanism may be easily actuated for accomplishing the stretching operation.

Having thus described my invention, what 75 I claim and desire to secure by Letters Patent is:

1. A wire stretcher including a support, a bracket mounted thereon and including spaced arms, a winding shaft mounted to 80 extend between the said arms, a worm shaft bracket mounted upon the uppermost of said arms and coöperating therewith to provide a bearing for the winding shaft, a worm shaft mounted upon the said bracket, 85 a worm mounted upon the said worm shaft, a worm wheel mounted upon the winding shaft to coöperate with the said worm with the worm shaft operable for rotating the winding shaft, a flexible element connected 90 to the winding shaft, and means associated with the said flexible element and adapted for engagement with a wire.

2. A wire stretcher including a support, 95 a bracket mounted thereon, said bracket being formed from a strip connected intermediate its ends and at its terminals to the support with the extremities of the said strip rebent to provide arms projecting laterally from the support and braced at their 100 outer extremities by the rebent portions of the strip, a winding shaft journaled at its extremities upon the said arms, means carried by the bracket for rotating the said shaft, a flexible element connected to the 105 shaft, and means associated with said flexible element for engagement with a wire.

3. A wire stretcher including a support, a bracket mounted thereon, the said bracket being provided with arms extending laterally from the support and formed at one extremity with a rebent portion extending from one of said arms, a winding shaft journaled between the said arms, means for rotating said shaft housed by the rebent 110 portion of the said bracket, a flexible element connected to the said shaft, and means associated with said flexible element for engagement with a wire.

In testimony whereof I affix my signature. 120

WALTER K. HOUSER. [L. S.]
